UNITED STATES PATENT OFFICE.

HARRY J. SCHUYLER, OF LOUISVILLE, KENTUCKY.

STOVE.

Specification of Letters Patent. Patented Apr. 27, 1915.

1,137,538.

Application filed December 4, 1914. Serial No. 875,415.

To all whom it may concern:

Be it known that I, HARRY J. SCHUYLER, a citizen of the United States, and a resident of Louisville, in the county of Jefferson and State of Kentucky, have invented certain new and useful Improvements in Stoves, of which the following is a specification.

My invention relates to heating stoves, and one of the main objects thereof is to provide such a stove wherein the air supplied to the fuel is pre-heated, thereby resulting in great fuel economy.

A further object is to provide top, intermediate, and lower chambers, the first of which is adapted to be placed in communication with either said lower chamber or with the escape flue of said stove, in the normal operation of the stove or to prevent back-draft when the stove door is opened.

20 A further object is to provide a fire-pot of considerably less diameter than the stove whereby an air space is provided around the same, to assist in heating the air on its way to the fuel and to increase the heat radiating surface of the stove; and a further object is to provide means for supplying a desired amount of oxygen directly above the fire by means of what I term an over-draft.

My invention is fully described in the following specification, of which the accompanying drawings form a part, in which like reference characters are used to designate like parts in each of the views, and in which:—

35 Figure 1 is a central, vertical, section taken through a stove constructed in accordance with my invention, on the line 1—1 of Fig. 3; Fig. 2 is a similar section at right angles to that shown in Fig. 1; Fig. 3 is a plan view, partly broken away; Fig. 4 is a section taken on the line 4—4 of Fig. 1; and Fig. 5 is a fragmentary front elevation thereof.

In the drawings forming a part of this application I have shown a present preferred form of embodiment of my invention, comprising the cylindrical shell 6 having a substantially central, horizontal, partition 7 therein supporting the fire-pot 8 which has the usual grate 9 at the lower end thereof, said partition 7 being perforated at desired points, as shown at 10, Figs. 2 and 4. Said shell is provided with a fuel-door 11, an air-tight ash-door 12, an air supply opening 13 in the top thereof provided with a movable closure 14, and a flue 15 for the escape of

the burnt gases or other products of combustion, and said fire-pot 8 is provided with a plurality of openings 16 therethrough adjacent the upper edge thereof, but below the 60 partition 7.

Arranged beneath the opening 13 is a pan-shaped member 17 secured to the top of the stove and provided with an opening 18 on the side thereof next to the flue 15, and with 65 openings 19 corresponding in number to the perforations 10 in the partition 7, and with a slot 20 for the passage of the arm 21 of a plate 22 slidable over the bottom of the member 17 and guided by means of a bolt 23 70 arranged in said member and in a slot in said plate 22, and the outer end of said arm 21 is slotted at 24 to receive the upper arm 25 of a lever pivoted at 26 and having a lower arm 27. The upper edge of the fire- 75 door 11 is flanged, as shown at 28, to engage the lower end of a dog 29 pivoted at 30 and the upper end of which normally bears against the inner surface of the arm 27 of said lever. Pivoted at 31, to the top of the 80 stove, is a cam 32 which rests against the upper lever arm 25 and is provided with a handle 33, and, when said handle is depressed, the plate 22 is moved outwardly, and the dog 29 is actuated to force the door 85 11 open; when said door is closed, said dog actuates the lever to move said plate inwardly into normal position.

The damper plate 22 has two wings 34 provided, each, with a plurality of perforations 35 in normal register with corresponding openings 19 beneath said wings, but, if the plate 22 is moved for a distance equaling or slightly exceeding the diameter of the said perforations, all of said openings 19 95 are covered by the corresponding wings, and this forms an important feature of my invention. The plate 22 also carries, at the end opposite the arm 21, a vertical damper 36 which normally closes the opening 18, 100 whereas the plate 22 normally uncovers the openings 19, but, if the plate 22 be moved toward the front of the stove, in the opening of the fire-door, the opening 18 is uncovered, and the openings 19 are covered, the distance 105 of movement of the plate 22 being gaged to insure this result. Connecting each of the openings 19 with a corresponding perforation 10 is a tube 37, there being four of such tubes on each side of the central line of the 110 stove, from front to back and from side to side, in the form shown, although they may

be of any desired number, and in any desired arrangement, but it will be noted that no air can enter the chamber X^2 from the chamber X except through said tubes 37, the 5 ash-pit X^3 , the grate 9, and the fuel, not shown, and this is the only air which is supplied to the fuel; a slight quantity of this air may, however, enter the fire-pot as already described by way of the openings 16 10 to supply oxygen to the flames, this being limited by reason of the size and number of said openings 16, and it will thus be seen that the air for the fuel must come through the opening 13 and be under control by 15 means of the closure 14.

Normally, the air from the opening 13 passes through the tubes 37 and to the fire-pot, and through the fuel, the said tubes being heated because of their position over the 20 fuel in the fire-pot, and said air is heated by the time it reaches the ash-pit, thus saving the amount of fuel ordinarily required to raise the air to this temperature, and this heated air also serves to maintain the ash-pit 25 at a high temperature, thereby causing heat radiation over the entire external area of the chambers X^2 and X^3 , and, for a desired degree of heat in a room, this also results in a saving of fuel. The products of combustion 30 are free to pass upwardly through the flue 15 and to the chimney in the usual manner, a damper being provided in this flue if desired, although not shown, but no air may enter the stove through either of the doors 35 11 or 12. If, with the parts in this position, the door 11 is opened by means of the handle 33, the passage of air through the tubes 37 from the opening 13 is prevented, and the air from said opening passes through the 40 opening 18 to and upwardly through the

flue 15, thereby preventing a back-draft through the stove, and eliminating the scattering of ashes in a room and the diffusion of the gases from the fuel through the air of said room.

It will thus be seen that I provide a stove in which the entire height thereof radiates heat with a minimum fuel consumption because of the pre-heating of the air supplied to said fuel, and I also provide means for preventing a back-draft; while I have shown certain details of construction, I do not limit myself thereto, but may make changes there-over, within the scope of the following claim.

Having fully described my invention, what I claim as new, and desire to secure by Letters Patent, is:

A stove, comprising a shell, a partition intermediate the height thereof, a fire-pot depending from said partition, a pan shaped member in the top of said stove provided with a plurality of openings through the bottom thereof and with an opening in the side thereof, an outlet for said stove, a controlled inlet at the top of said stove, above said pan, a tube leading from each bottom opening of said member to and through said partition, and a plate slideable in said member and serving to close the side opening and open the bottom openings of said member, or to open said side opening and close said bottom openings.

In testimony whereof I have signed my name to this specification in the presence of 75 two subscribing witnesses.

HARRY J. SCHUYLER.
